DESIGN FOR A VELOCIPED FRAME MEMBER

Einar A. Anderson, Hammond, Ind.

Application December 14, 1938, Serial No. 81,780

Term of patent 14 years

To all whom it may concern:

Be it known that I, Einar A. Anderson, a citizen of the United States, residing at Hammond, in the county of Lake and State of Indiana, have invented a new, original, and ornamental Design for a Velocipede Frame Member, of which the following is a specification, reference being had to the accompanying drawing, forming part thereof.

Figure 1 is a side elevational view of a velocipede frame member showing my new design.

Figure 2 is a top plan view thereof.

Figure 3 is a rear elevational view of the velocipede frame member.

I claim:

The ornamental design for a velocipede frame member, substantially as shown.

EINAR A. ANDERSON.
